Attorneys.

UNITED STATES PATENT OFFICE

GEORGE ADAMS, OF STURGIS, KENTUCKY

MINE LAYOUT

Application filed October 29, 1928. Serial No. 315,739.

This invention aims to provide a mine layout in which a long continuous face, exposed for working, extends entirely around the mine, the worked part of the mine being at 5 the center of it, and the coal which is to be cut lying at the periphery of the mine. Another object of the invention is to provide a novel means whereby there will be an adequate circulation of air around the bounding 10 face of the mine, which is being worked. A further object of the invention is to provide a novel form of endless track whereby the coal or other material which has been mined can be brought easily and rapidly to the main shaft. 15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, within the 25 scope of what is claimed, changes in the precise embodiment of the invention shown can be made without departing from the spirit of the invention.

In the accompanying drawings:—

The invention is disclosed in a single dia- 30 grammatic view, which is a horizontal section.

In the drawing, there is shown a mine com- 35 prising a chamber 1 bounded by a continuous working face 2. A wall 3, made of brattice work, extends from the floor of the mine to the roof of the mine and defines a compartment 4 in the central part of the chamber 1. The part of the mine that has been worked is within the compartment 4. The numeral 5 marks 40 the pillars that have been left standing between the floor of the mine and the roof thereof. In the event that it is desired to remove all of the coal, the pillars 5, of course, may be made of concrete or any other suitable substance. 45

A main shaft indicated at 6, extends down- 50 wardly through the roof of the mine, into the compartment 4. Along certain of the pillars 5 extends a wall 7 of brattice, the wall 7 ex- 55 tends from the floor of the mine to the roof

of it. The wall 7 forms the back of the main shaft 6, where the cage comes down into the compartment 4. Arranged parallel to the wall 7 are other walls 8, which are spaced apart to form an inlet 9 to the main shaft 6. 55

The walls 7 and 8 form a diagonal alley 10 extending from one corner of the compartment 4 to the opposite corner. At one end of the alley 10 there are doors 11. At the opposite end of the alley 10 there are doors 12. Doors 14 are extended across the alley near to the doors 12, the doors 14, however, being spaced at some distance from the doors 12. Doors 14a, corresponding to the doors 14, are located adjacent to the doors 11. Between the doors 14 and the doors 12, there is an opening 15 in the wall 8, this opening being disposed opposite to an opening 16 in the wall 7. There is an opening 17 in the wall 7 near to the doors 11. 60 Opposite to the opening 17 there is an opening 18 in the wall 8. The numeral 19 designates an air shaft extended down into a brattice work box 20 extended between the floor and the roof of the mine, the side walls 21 of the box 20 being joined to a part of the wall 3 and to one of the pillars 5, so that the air shaft 19 can discharge, as indicated at 22, into the chamber 1, between the wall 3 and the working face 2 of the mine. 65 The compartment 4 has an air inlet 23 located close to the place where the air shaft 20 discharges at 22 into the chamber 1. Near to the air inlet 23 is a door 24 that extends between one of the pillars 5 and the working face 2. The numeral 25 marks a door extended between the wall 8 and the back end of the box 20 that forms the lower end of the air shaft 19. The door 25 is located at one corner of the main shaft 6. 70

Oppositely disposed loop-shaped tracks 26 are mounted on the floor of the mine. The outer portions 27 of the tracks 26 cooperate to form a transportation means extended entirely around the chamber 1 in convenient relation to the working face 2. The tracks 26 include inner portions 28 extended lengthwise of the alley 10 and leading to the shaft 6. 75

The mine cars (not shown) may be pushed by motors around the tracks 26, the coal 80

that is mined from the working face 2 being loaded into the cars and carried to the main shaft 6. The cars can be run in one direction on each track, and there will be little danger because a person on or near either track can be assured that the cars are always running in one direction, and will not have to watch in two opposite directions. The plan shown, as to the tracks, will enable a mine owner to do away with mules or other beasts of haulage, and the mortality amongst drivers will be cut down to nothing.

The air comes down the air shaft 19 and passes at 22 into the working space around the compartment 4 and between the wall 3 and the working face 2. The door at 24 constrains the air to move to the right, as shown by the arrows, and the air, fresh from the shaft 19, sweeps around the entire working face 2 until the door 24 again is encountered. The air thereupon enters the central part of the mine, which has been worked, the air going in by way of the inlet 23. From the inlet 23, the air follows a spiral course, to the main shaft 6, the means for causing the air to move as aforesaid being the door 25, the opening 15, the curtain 14, the door 12, the opening 16, the opening 17, the door 11, the opening 18, the door 25 again, and the opening 9.

The coal is mined out along a number of long straight faces, as shown at 2, and the coal is not driven ahead of the air, explosions and fires being kept down accordingly. The coal cutting is not done in advance of an adequate supply of air, and there will be no pocketing of gas.

The miners cut around the outer wall of the mine and there is no occasion for taking the mining machine out from under the coal, save for repairs.

The plan outlined may be used in slope mines, as well as in shaft mines.

I claim:—

- 45 1. In a mine comprising a chamber bounded by a continuous working face and having a main shaft extending down to said chamber, oppositely disposed loop-shaped tracks the outer portions of which cooperate to form a transportation means extended entirely around the chamber in convenient relation to said working face, the loop-shaped tracks comprising inner portions leading to the shaft.
- 55 2. In a mine comprising a chamber bounded by a continuous working face, a wall defining a compartment in the central part of the chamber, a main shaft leading down to the compartment, an air shaft discharging into the chamber, between the wall and the working face, the compartment having an air inlet located close to the air shaft, a door between the shaft and the inlet and extended from the wall to said continuous working face whereby the air may circulate entirely

around the said continuous working face, and means for directing the air in a spiral course from the inlet through the compartment and to the main shaft.

3. In a mine comprising a chamber bounded by a continuous working face, a first wall defining a working compartment in the central part of the chamber, normally closed doors at opposite portions of the first wall, approximately parallel second walls forming an alley within the compartment, normally closed doors at the ends of the alley, and disposed in facing relation to the first specified doors, a main shaft leading downward into the alley, one of the second walls having an inlet communicating with the shaft and with the compartment, a box opening through the first wall and communicating with the chamber externally of the compartment, a shaft leading downwardly to the box, a door normally closing the space between the first wall and the working face, and a closure extended between the box and said one of the second walls, at one side of the inlet, the last specified door being located closely adjacent to the box.

In testimony that I claim the foregoing as my own, I have hereto affixed my signature.

GEORGE ADAMS.
